UNITED STATES PATENT OFFICE

2,323,271

GRATING

Richard J. Barry, New York, N. Y., assignor to
Walter Edward Irving, Glenbrook, Conn.

Application February 19, 1942, Serial No. 431,503

14 Claims. (Cl. 94—13)

This invention relates to improvements in gratings and more particularly to a novel means of coupling grating panels in edge to edge relation to provide a continuous grating of a required area.

The invention set forth herein constitutes an improvement over the gratings set forth in the present pending patent applications Serial No. 358,598, filed September 27, 1940, and a divisional application thereof Serial No. 372,706 filed January 2, 1941, in which I am a joint inventor with Carl Rasmussen.

The primary object of this invention resides in a continuous grating and means for releasably connecting the grating panels together for emergency use as portable air field mats and for the formation of other large grating areas.

One of the present type of grating air field mats and means of connecting the grating panels is dangerous to those handling them, for they provide pointed coupling bars along the outer edges of the panels which cause injury to the handlers and tear their clothing. Another grating panel section with which I am familiar is constructed with broken bars about the sides and ends thereof, or which have their side and end bars provided with wing-type connectors. The former construction is weakened by reason of the broken bars, and the latter produces a hinge effect when two or more panels are coupled together which effect weakens the continuity of the mat formed by the coupled panels. Furthermore, the means of connecting the panel sections above referred to are expensive of construction, for the broken bar construction requires the making and handling of small pieces during fabrication of the grating panels. The wing-type connector construction requires the making, handling and riveting of relatively small pieces to the outside edges of the panels after the same are made up. Also, the ends of broken bars and wing connectors are easily bent in handling and transportation which necessitates time and labor to straighten out for assembly in the field. Whereas the two aforementioned constructions of grating panels have been placed into practice and the broken bar structure is superior to the wing-type connector method, grating manufacturers employing welding methods cannot economically use it because of the extra work and expense involved in making the outside bars broken and in pieces. A third type of mat section with which I am familiar and which is known as the "Pierced steel plank type" also has certain of the above mentioned objections, for each mat section consists of a perforated panel having bent tongues along one of the

edges and tongue receiving slots along the opposed edge. These tongues are exposed to bending and breakage during handling and may not be in position for forming an interlock with the slots of a companion panel.

Some of the features of the invention are to provide a grating panel having continuous bars on the outside edges which permits edge bars of adjacent panel units to be locked flush against each other, thereby eliminating any hinging action between adjacent panel units; which eliminates danger of bending of side bars in handling and in transit; which hastens fabrication of the panels in the shop, and assembly of the same in the field; which standardizes all longitudinal bars in the panel as to length and bends at the ends, and all transverse end bars as to length; which reduces scrap and waste in manufacturing; which eliminates the danger of injury to a person handling the panels and any liability of tearing one's clothes during handling; and by use of continuous outside bars, the same may be welded together with all other bars in the panel unit.

Another feature of the invention is to provide a novel construction of releasable coupling means between adjacent panels consisting of suitably spaced C-shaped coupling members captively slidable on the meeting side bars of adjacent companion panel units, the C-shaped coupling members on one of the meeting bars having interlocking engagement with the meeting bars of companion panel units, said C-shaped coupling members being freely engageable with the side bar of a companion panel unit upon positioning of the panel sections edge to edge, so that an assembler need only hammer the C-shaped coupling members to locking positions along the meeting side bars, said C-shaped members being held against sliding to releasing position by stops struck out from one of the meeting side bars, which stops may be struck a hammer blow to restore the bar to a straight form to enable sliding of the coupling members to release position when separation of the panels for removal, repair, or replacement is desired.

Other novel features of the invention will become apparent as the following specification is read in conjunction with the accompanying drawings, in which:

Figure 1 is a top plan view of three grating panels showing them separated and partly broken away.

Figure 2 is a view similar to Figure 1 on an enlarged scale and showing the three grating

panels in coupled relation to form a continuous grating surface.

Figure 3 is a detail perspective view of the coupling means between the side bars of two grating panels, the panels being shown in separated position.

Figure 4 is a view similar to Figure 3 but showing the meeting bars of two adjacent panels in coupled engagement.

Figure 5 is a sectional side elevational view of the bar coupling means in released position.

Figure 6 is a view similar to Figure 5, but illustrating the coupling member in coupling position.

Figure 7 is an enlarged vertical transverse sectional view on the line 7—7 of Figure 5.

Figure 8 is a fragmentary top plan view partly in section of the meeting bars of two adjacent grating panels, the coupling slide members being shown in locking position and held against sliding to release position by bending one of the bars outwardly relative to the other at a point intermediate the spaced apart coupling members.

Figure 9 is a side elevational view of one of the grating panels per se.

Figure 10 is an end elevational view of one of the grating panels per se.

Figure 11 is a sectional side elevational view of a modified form of stop means for limiting sliding of the coupling members from coupling to release position, the stops being illustrated in normal position prior to being struck to stop forming position.

Figure 12 is a top plan view of the modification shown in Figure 11 and showing the stops in struck-out obstructing position.

Figure 13 is a sectional side elevational view of a modification to facilitate the guiding of the coupling members to coupling position; the coupling members being illustrated in release position in full lines and in locking position in dotted lines.

Figure 14 is a top plan view of the modification shown in Figure 13, and showing the coupling members in locking position.

Referring to the drawings by reference characters and at present to the form of the invention illustrated in Figures 1 to 10 inclusive, the numeral 10 designates one metal grating panel or unit in its entirety. For the construction of a continuous grating, a number of metal grating panels 10 are provided as shown in Figs. 1 and 2, which have abutting ends and sides coupled together in a novel manner hereinafter described. The panels 10 are all of the same size, shape, and construction to render them interchangeable, and a description of one of such grating panels will suffice for the others.

A grating panel 10 is elongated rectangular in form and of any desired length and width which facilitates ease of handling during manufacture, transit, and assembly of the panels in use for the making of continuous grating. In practice, dimensions of approximately twelve and one half feet length, and between one to two feet width have proven satisfactory for convenient handling of the grating panel but such dimensions are not to be construed as limitation of the scope of the invention, for the panels may be made in other sizes if desired.

The panel 10 is constructed of flat metal bars or strips arranged on edge, and which define the grating meshes. The panel includes an elongated rectangular frame F comprising straight parallel side bars 11—11, and straight end bars

12—12a. The ends of the side bars 11—11 are provided with right angular inwardly bent flanges 13 to which the respective ends of the end bars 12—12a are riveted or welded as at 14. Equidistantly spaced and disposed parallel to the side bars 11—11 is a series of straight bars 15, the ends of which are bent at right angle to provide flanges 16 which abut the adjacent end bars 12—12a and are secured thereto by rivets 17 or welding. If the meeting ends of the bars are welded, the flanges 16 may be eliminated. The transverse spacing of the bars 11—11 from the bars 15 corresponds to the spacing of the latter from each other.

15 In the spacing between the bars 15 and between the outermost bars 15 and side bars 11—11 there are strips 18 bent into appropriate zig-zag form and permanently secured at their point of contact to the respective bars 11 and 15 by rivets 19 or by welding. Thus, all of the bars 11, 12, 12a, 15 and 18 are rigidly and permanently united in a unitary panel structure, the open spaces between adjacent bars constituting meshes.

25 Each side bar 11 beginning with the mesh next to the corner mesh, is provided with equidistantly elongated reduced portions 20. These reduced portions 20 are formed by cutting away opposite edges of the bar 11 and are disposed medial of the height of the bar. The cut-away portions provide opposed notches 21—21 in the bar, the end walls of which are inclined as at 22. The reduced portions 20 in the bar 11 are disposed at alternate meshes along the length of 30 the bar as best illustrated in Figures 1, 2, and 9. Slidably mounted on each bar 11 within each of those meshes intermediate those in which the reduced portions 20 are formed, are a pair of C-shaped coupling members 23—23. One C-shaped coupling member 23a is slidable on each bar 11 within the length of each corner mesh. Each coupling member 23 and 23a has its open mouth 24 facing outwardly and the size of the mouth is greater than the width of the reduced portions 20 to facilitate the free insertion of the reduced portion 20 of one panel 10 into the mouths 24 of the coupling members of a next adjacent panel 10 during the forming of a continuous grating as will be more fully explained 45 hereinafter. The cross sectional space within each C-shaped coupling member is of a size to receive the cross sectional areas of the abutting side bars 11 of a pair of adjacent grating panels.

50 The end bar 12 is provided with two suitably spaced reduced portions 20a which are similar to the reduced portions 20. In this instance the reduced portions 20a are respectively disposed within those meshes next to the corner meshes as best illustrated in Figures 1, 2 and 10. Only 55 one of the ends of the notches formed by providing the reduced portions 20a have their ends inclined as at 22a, however, in instances where space permits, both ends may be inclined. The inclined end walls 22a are those disposed nearest the ends of the bar 12.

56 The end bar 12a is of uniform shape and has two suitably spaced C-shaped coupling members 23b slidably mounted thereon within those meshes next to the corner meshes as best illustrated in 60 Figures 1 and 2. The C-shaped coupling members 23b are identical in construction as the coupling members 23 and a further description of the same is not believed necessary, except that their open mouths face outwardly to confront the reduced portions of companion bars of adjacent

panels to be connected to form a continuous grating or mat.

In assembling the panels 10 as illustrated in Fig. 1, it is first desirable to slide the pairs of coupling members 23-23, to releasing position toward each other, that is, to a position substantially midway between adjacent bends of the adjacent zig-zag strips 18, so as to be disposed in a position to receive the respective reduced portions 20 of the next panels to be connected. The single coupling members 23a are slid to a releasing position adjacent the end bars 12 and 12a. After placing one panel 10 flat upon the ground or other supporting surface, a second companion panel 10 is likewise placed in staggered relation thereto and adjacent side bars 11 of the two panels are brought into parallel abutting engagement with the open sides of the coupling members 23 of the side bar 11 of one panel in confronting relation to the reduced portions 20 of the companion panel. An operator, now, with the aid of a hammer may strike the members 23-23 to slide them to locking position, clear of the ends of the reduced portions 20. Also, the single coupling members 23a will receive one of the reduced portions 20 and is driven to locking position clear of one end thereof. Two panel sections are now connected, side by side and in staggered relation. Other panels 10 may be similarly connected to the outer free sides of the two connected panels to form a grating surface of the desired width.

For connecting the panels 10, end to end, a slightly different procedure takes place. The panel 10 may be considered as having a female end on which the coupling members 23b are mounted, and a male end on which the reduced portions 20a are provided in the end bar 12. The male end of one panel is brought into edge to edge relation with the female edge of a companion panel, or vice versa. The coupling members 23b are slid to releasing position prior to bringing the ends of the panels together, whereupon the reduced portions 20a will freely enter the mouths of the coupling members 23b, after which an operator hammers the coupling members 23b outwardly toward the inclined walls of the notches formed by the cutting away of the bar 12 to form the reduced portions 20a. The third panel overlaps the side of the first mentioned panel, and the confronting side bars 11-11 of these two panels are joined together by the coupling members 23 and 23a of one panel being slid to locking position on the bar 11 of the other panel as best illustrated in Figure 2. Any number of panels 10 may be connected end to end to provide a grating surface of a desired length.

After the coupling members 23, 23a, and 23b, have been driven home to locking position, they may be held against accidental sliding movement to release position by several different means, two of such means being illustrated in Figures 8, 11, and 12. In Figure 8, a pointed instrument may be inserted between the reduced portions 20-20a and the adjacent confronting side rail or end rail 12a respectively, and a hammer blow imparted to the instrument to cause the same to force the reduced portions 20 and 20a outwardly to bulged shape. The bulged shape or outwardly deformed reduced coupling portions act as stops for limiting the sliding movement of the C-shaped coupling members to releasing position. However, the deformed coupling portions may be flattened to their original positions by striking the same

a blow with a hammer when it is desired to slide the C-shaped coupling members to release positions for purposes of disassembling the connected grating panels or when repair or replacement of the same is in order.

In Figures 11 and 12, the bar 11 is slit on horizontal lines coextensive with the ends of the top and bottom edges of the reduced portions 20 as indicated by the numeral 25 to provide pointed bendable lugs 26. The lugs 26 are bent outwardly by the use of a suitable instrument to the position shown in Figure 12, where they are in obstructing position to prevent sliding movement of the pair of coupling members 23-23 to release positions. The lugs 26 may be bent to original positions within the plane of the thickness of the bar from which they are formed when it is desired to slide the coupling members 23-23 toward each other to release position.

In Figure 14, the end walls of the opposed notches 21 are beveled outwardly as at 27 for engagement by the walls of the mouth opening 24 of the C-shaped coupling members 23 when they are driven from release to locking position. The beveled surfaces 27 act to guide the coupling members to locking engagement with the bar 11 on which the reduced coupling portion 20 is formed.

From the foregoing description, it will be understood that the grating panels and coupling means carried thereby are convenient for rapid assembly and coupling of the panels, and also, for convenient and rapid dismantling of the continuous grating, or for removal and replacement of a damaged panel located in any position in the length and width of the assembled grating. Any one of the panels may be uncoupled by merely driving those coupling members to their releasing position which fasten the panel to adjoining panels, after which the uncoupled panel may be freely lifted from the assembly.

In addition to the above stated advantages, the continuity of the side and end bars of the panel and the novel coupling means, permits the close coupling of the meeting outer bars, and prevents any objectionable hinge effect between the coupled panels. Also, the C-shaped coupling members are captively slidable on their respective supporting bars and their sliding movement is restricted by the sections of the various bars forming the meshes.

While there has been shown and described what is considered to be the preferred embodiments of the invention, it is to be understood that such changes in construction and design as come within the scope of the appended claims may be resorted to if desired without departing from the spirit of the invention.

Having thus described the invention, what I claim as new and desire to secure by Letters Patent of the United States, is:

1. A sectional grating including a panel having a side bar, a reduced portion provided in said side bar, a companion panel having a side bar flatly abutting the first side bar, and a pair of C-shaped coupling members slidably mounted upon the second side bar having their open sides facing the first side bar to freely receive the reduced portion, said C-shaped coupling members being slid in opposite directions beyond the ends of the reduced portion to cause the same to clampingly embrace both side bars to prevent separation of the panels one from the other.

2. A sectional grating as set forth in claim 1, including means bent outwardly from the first

side bar at the ends of the reduced portion and disposed in the path of sliding movement of the respective coupling members toward each other when in spaced apart coupling position to prevent accidental uncoupling of the panels.

3. A sectional grating including a panel having a side bar, said side bar having opposed notches in the longitudinal edges thereof, a companion panel having a side bar flatly abutting the first side bar, and a pair of C-shaped coupling members slidably mounted upon the second side bar having their open sides facing the first side bar and clampingly embracing the first side bar beyond and adjacent the ends of said notches, said notches being of a length greater than the combined widths of the pair of coupling members whereby the coupling members may be slid toward each other to release position within the confines of the length of the notches to facilitate the uncoupling and subsequent coupling of the panels.

4. A sectional grating including a panel having a side bar and open meshes along said side bar, C-shaped coupling members slidably upon said side bar within the limits of certain of said meshes and having the open sides facing outwardly; a companion panel having a side bar and open meshes along the last named side bar, the last named side bar having sets of opposed notches in the longitudinal edges thereof, each set of opposed notches being disposed within the limit of certain of the meshes of the companion panel, the bars being arranged in abutting engagement with sets of notches in opposed relation to the C-shaped coupling members to facilitate the passage of the open sides of the coupling members through the opposed notches to enable the sliding of the coupling members beyond the ends of the respective notches to coupling engagement with the notched side bar.

5. A grating section comprising an elongated rectangular shaped panel having a structure forming the grating meshes bounded by straight continuous side bars, the two opposed longitudinal side bars having reduced portions spaced therealong, said reduced portions being within the limit of alternate meshes along the said bars, and C-shaped coupling members slidably mounted on said longitudinal bars within the limits of the other of said meshes, the open sides of the C-shaped coupling members facing outwardly to enable the same to be brought into coupling relation to the reduced portions of a companion panel to facilitate the sliding of the coupling members onto the complementary side bar of a companion panel.

6. A grating section comprising an elongated rectangular shaped panel having a structure forming the grating meshes and including straight continuous end bars, one of the end bars having reduced portions within the limits of suitably spaced meshes along said bar, and C-shaped coupling members slidably mounted upon the other end bar within the limits of those meshes corresponding to those aforementioned spaced meshes, the open sides of the C-shaped coupling members facing outwardly to enable the same to be brought into coupling relation to the reduced portions at the end of a companion panel to facilitate the sliding of the coupling members onto the complementary end bar of a companion panel.

7. A sectional grating including a grating panel comprising a structure forming grating meshes and including a bar forming a side of the closed

meshes at an edge of the panel, reduced portions provided in said bar and suitably spaced therealong within the limits of certain of the meshes, a companion panel comprising a structure forming grating meshes and including a bar forming a side of the closed meshes at an edge of the companion panel and arranged in abutting engagement with the first bar, and a series of C-shaped coupling members slidably mounted on the second

5 bar within the limits of certain of the meshes, said C-shaped coupling members having their open sides facing outwardly to respectively receive the reduced portions of the first bar when slid to release position and being slid beyond the 10 ends of the reduced portions to coupling position for coupling the panels together.

15 8. A sectional grating as set forth in claim 7, including means bent out from the bar of the first panel after the coupling members are slid to coupling position for preventing the accidental sliding of the coupling members to release position.

20 9. A sectional grating as set forth in claim 7, including prongs bent outwardly from the ends 25 of the reduced portions and disposed in the path of sliding movement of the coupling members to release position for preventing accidental sliding of the coupling members from coupling to release position.

30 10. A sectional grating as set forth in claim 7, including beveled guide surfaces provided on the first bar at the ends of the reduced portions in the path of sliding movement of the coupling members to coupling position for guiding the 35 coupling members onto the first bar for coupling engagement therewith.

11. A sectional grating panel including a panel having a side bar, said side bar having sets of opposed notches in the longitudinal edges thereof, said sets of notches being arranged at suitable spaced distances apart, a companion panel having a side bar flatly abutting the first side bar, and C-shaped coupling members slidably mounted upon the second bar having their open 40 sides facing the first side bar and clampingly 45 engaging the first side bar beyond the ends of the respective sets of notches, said sets of notches being of a length greater than the width of the respective C-shaped coupling members whereby the C-shaped coupling members may be slid to 50 release position within the confines of the length of the respective sets of notches to facilitate the uncoupling and subsequent coupling of the panels.

12. In combination, a pair of grating panels having straight continuous complementary outer bars arranged in side to side abutting relation, a substantially C-shaped coupling member slidably mounted on one of said bars and having its open side facing the other of said bars, the other of said bars having a reduced portion provided therein intermediate the ends thereof, said C-shaped coupling member receiving the reduced portion through the open side thereof and being slid to a position beyond one end thereof to cause the same to embrace both of the bars and prevent accidental separation of the grating panels.

13. A sectional grating including a panel having a side bar, a reduced portion provided in said side bar, a companion panel having a side bar intermediate the ends thereof flatly abutting the first side bar, a C-shaped coupling member slidably mounted upon the second side bar having its open side facing the first side bar, said C-shaped coupling member being of a cross-sec-

tional size to slidably embrace both side bars, said C-shaped coupling member receiving the reduced portion through the open side thereof and being slid to a position beyond one end of the reduced portion to cause the same to embrace both side bars to prevent accidental separation of the panels one from the other.

14. A continuous grating comprising in combination, a rectangular shaped grating panel having straight continuous side bars, a companion 10 grating panel having straight continuous side

bars, two corresponding side bars of the panels being arranged in parallel abutting engagement, C-shaped coupling members slidably and captive-ly mounted on one of the side bars and engaging the other side bar and having their open sides facing the last named side bar, said coupling members being engageable and disengageable with the last named side bar by means of reduced portions provided thereon for securing the panels together in side by side relation.

RICHARD J. BARRY.
